UNITED STATES PATENT OFFICE

142,452

DESIGN FOR A SURFACE TREATING MACHINE

Louis Vavrik, Rossford, Ohio, assignor to The
American Floor Surfacing Machine Company,
Toledo, Ohio, a corporation of Ohio

Application May 28, 1945, Serial No. 119,782

Term of patent 14 years

(Cl. D9—2)

To all whom it may concern:

Be it known that I, Louis Vavrik, a citizen of the United States and resident of Rossford, in the county of Wood and State of Ohio, have invented a new, original, and ornamental Design for a Surface Treating Machine, of which the following is a specification, reference being had to the accompanying drawing, forming a part thereof.

This is a continuation-in-part of applicant's application Serial No. D-115,458, filed September 25, 1944.

In the drawing,

Fig. 1 is a front perspective view of a surface treating machine showing my new design, and Figs. 2 and 3 are side and front end views, respectively, thereof.

Both sides of the machine are substantially the same in appearance.

The dominant features of my design are shown in full lines.

I claim:

The ornamental design for a surface treating machine, substantially as shown and described.

LOUIS VAVRIK.
